UNITED STATES PATENT OFFICE.

RICHARD E. BERTHOLD, OF FLUSHING, NEW YORK.

GAS-IGNITER.

1,086,435.

Specification of Letters Patent.

Patented Feb. 10, 1914.

Application filed January 22, 1913. Serial No. 743,432.

To all whom it may concern:

Be it known that I, RICHARD E. BERTHOLD, a citizen of the United States, and resident of Flushing, in the county of Queens and 5 State of New York, have invented certain new and useful Improvements in Gas-Igniters, of which the following is a specification.

This invention relates to igniting and re-10 igniting devices for gas burners, the object being to provide means whereby the gas issuing from an ordinary gas burner will be automatically ignited, and whereby, if the flame be extinguished without shutting off 15 the gas supply, as by blowing out said flame, it will be re-ignited and thus the danger of an escape of unburned gas be avoided.

In my improved igniter I employ a cata-20 lytic substance, with communicating fine platinum strands in the path of flowing gas, whereby, as is well known the catalytic sub-stance, as, spongy-platinum, and the plati-25 num strands become incandescent, resulting in the ignition of the gas.

25 A particular feature of the improvements consists in the method by which the igniting material is held in the presence of air to assist combustion, also in the means whereby it is protected from direct contact with the 30 flame which it ignites.

In the drawing: Figure 1 is an elevation of a gas burner with my igniting device applied thereto. Fig. 2 is a side sectional view thereof. Fig. 3 is a bottom plan view. Fig. 35 5 is a partial side section enlarged.

In said figures *a* indicates an ordinary burner tube with burner tip *b*. Attached to said burner tube, at the side thereof, as by a 40 band *c*, is a tube *d*, open at both ends. In-45 serted within tube *d* is a frame *e* having strung thereon a number of fine platinum strands *f* carrying one or more pellets of catalytic material, as *g*. A fine pilot tube, 45 as *h*, leads from the interior of burner tube *a* to a position below the open tube *d*. Said pilot tube *h* has an opening *h'* within burner tube *a* to receive gas, and an orifice *h''* to

permit a tiny jet of gas to ascend axially within tube *h* for the purpose of reacting, in 50 the presence of air passing through said tube, upon the catalytic material. The flame produced within tube *d* from the resulting incandescence of said catalytic material and the platinum strands, serves as a 55 pilot to ignite the larger volume of gas issuing from burner tip *b*, and, obviously, through recurrent actions the issuing gas will be reignited whenever extinguished while the gas flow continues. 60

It being necessary to protect the catalytic material from the deleterious action caused by flame contact therewith, and the heat of such contact, I provide a flame protector consisting of a transverse bar *i* between gas 65 orifice *h''* and the igniter material, said bar serving to spread apart the pilot flame rising from said orifice *h''*, whereby said flame is prevented from coming into contact with said igniter material, and whereby the heat 70 zone within tube *d* extends up at the sides of said igniter material instead of taking a path axially through said tube and thereby attacking said igniter material. The protector bar *i* may be hollow, as seen, and open 75 to the atmosphere at both sides thereby being cooled through the action of passing air.

I claim:

A gas igniter comprising a burner tube, an adjacent open tube parallel therewith, 80 catalytic igniting material supported axially within said open tube, a pilot tube communicating from said burner tube to said open tube, with an orifice axially below said igniting material, and a transverse bar between 85 said igniting material and pilot orifice to protect the former from the flame contact and heat of the latter.

Signed at the borough of Manhattan, in the city, county, and State of New York, 90 this 21st day of January, A. D. 1913.

RICHARD E. BERTHOLD.
